(57) **CLAIM**

The ornamental design for a brassiere with a pocket, as shown and described.

DESCRIPTION

FIG. 1 is a front elevation view of a brassiere with a pocket showing our new design;

FIG. 2 is a rear elevational view thereof, shown with cross-sectional markings taken along 8—8.

FIG. 3 is a right elevation view thereof;

FIG. 4 is a left elevation view thereof;

FIG. 5 is a top plan view thereof;

FIG. 6 is a bottom plan view thereof;

FIG. 7 is an isometric view thereof; and,

FIG. 8 is a cross-section view of the pocket.

The broken lines in the drawings depict environmental subject matter only and form no part of the claimed design.
